UNITED STATES PATENT OFFICE.

CHARLES L. SAMPSON, OF ST. LOUIS, MISSOURI, ASSIGNOR OF ONE-HALF
TO THOMAS B. HOOPER, JR., OF SAME PLACE.

REIN-HOLDER.

SPECIFICATION forming part of Letters Patent No. 242,225, dated May 31, 1881.

Application filed November 19, 1880. (No model.)

To all whom it may concern:

Be it known that I, CHARLES L. SAMPSON, of the city of St. Louis, in the State of Missouri, have invented a certain new and useful Improvement in Rein-Holders, of which the following is a full, clear, and exact description, reference being had to the accompanying drawing, making part of this specification.

The drawing is a perspective view of the device.

A is a plate, having holes *a* for screws or rivets, by which it is attached to the dash-board, seat, or any other part of the vehicle where it will be within easy reach of the driver. In attaching it to the head-board or seat or side of a vehicle wood-screws may generally be used; but in attaching the holder to a leather dash-board or to any thin object I prefer to rivet it to a plate on the opposite side of the board to the holder, the rivets extending through both plates; or the means of attachment may be screws screwing into either the holder or plate aforesaid.

B is a bent bar formed in one piece with or attached to the screw or rivet plate A, and constituting the holder proper. The bar B has two S-shaped portions or return-bends, *b b'*. The portions *b'* of the bar B between the re-

turn-bends and between the outer bend and the end may be straight and about parallel with each other. The bar B forms a sort of double catch, through which the reins are woven by being first passed through the space C and then through the space D, as indicated in dotted lines. When the reins are thus placed in the holder a frictional hold will be had on the reins, which will prevent them being drawn out in the direction of their length.

I do not confine myself to any particular material for use in construction of the holder. It may properly be made of steel, iron, or brass, either flat or round or of other section. Neither do I confine myself to the described means of attachment to the vehicle. It may be permanently or removably attached.

I claim as my invention—

The rein-holder herein described, consisting of bar B, having base-plate A for attachment to the vehicle, and S-shaped portions *b b' b' b'*, forming spaces C and D for threading the reins through, as shown and described.

CHARLES L. SAMPSON.
